TELEPHONE BOOTH

Donald Michael Genaro, Haworth, N.J., John Niel Mc-
Garvey, Drexel Hill, Pa., and Frederick Allen Rose-
brock, Greenfield, Ind., assignors to Bell Telephone
Laboratories, Incorporated, Murray Hill and Berkeley
Heights, N.J.

Filed July 16, 1971, Ser. No. 163,556

Term of patent 14 years

Int. Cl. D25—99

U.S. Cl. D13—1 L

FIG. 1

FIG. 2

FIG. 3

FIG. 1 is a front perspective view of a telephone booth showing our design with the access door shown in the open position;

FIG. 2 is a front perspective view with the access door shown closed; and

FIG. 3 is a rear perspective view thereof.

The top and bottom of the booth are substantially plain. We claim:

The ornamental design for a telephone booth, substantially as shown and described.
